(57) **CLAIM**

The ornamental design for proximal connector for an endoscope assembly, as shown and described.

DESCRIPTION

FIG. 1 is a perspective view of a proximal connector for an endoscope assembly;

FIG. 2 is another perspective view of the proximal connector;
FIG. 3 is an enlarged perspective view of the proximal connector;

FIG. 4 is a front plan view of the proximal connector;

FIG. 5 is a side plan view of the proximal connector;

FIG. 6 is a top view of the proximal connector;

FIG. 7 is a bottom view of the proximal connector; and,

FIG. 8 is a perspective view of the proximal connector.
